[57] ABSTRACT

A device of cylindrical shape which includes a lower playing surface on which a multiple number of balls are placed in close proximity with each other. The upper portion of the device includes a sleeve and post member which is slideable upon a bar in order to position an adjustable trough having spring loaded means for urging a ball at any angle desired down into the cylindrical device so as to cause impact with the multiple number of balls.

FIG. 1

FIG. 3

FIG. 2

INVENTOR.
JOHN L. RONDEAU

BARREL POOL APPARATUS INCLUDING SPRING PROJECTOR

This invention relates to games, and more particularly to a barrel type game device.

It is therefore the primary purpose of this invention to provide a game device which will include barrel means with a lower surface therein for positioning a plurality of balls to be struck from a shooter ball at the upper extremity of the barrel device, the result being that the plurality of balls will be scattered so that they may be individually played into any one of a plurality of apertures within the playing surface.

Another object of this invention is to provide a game device which will be a competitive game and will have a transverse bar member on the interior of the barrel upon which will be slideable a sleeve, the sleeve being held stationary by wing nut fastener means when the sleeve is in place in the desired position and the sleeve will carry a post member having a trough member at its extremity which will be adjusted to any desired angle by means of a wing nut fastener.

Another object of this invention is to provide a device of the type described which will have a spring loaded lever on the trough member, the spring having sufficient tension so as to retain the shooter ball within the trough member until the lever is manually activated.

A further object of this invention is to provide a device which will require a degree of skill in order to position the trough so as to deliver the shooter ball for impact with a specific ball of a plurality of playing balls in order that they may be deposited within any one of a plurality of apertures within the playing surface of the barrel and the device also includes an angularly positioned chute spaced apart from the playing surface and beneath it for directing the placed balls towards the front portion of the device in order that they may be retrieved therefrom through an aperture through the wall of the barrel portion of the device.

Other objects of the present invention are to provide a barrel pool game device which is simple in design, inexpensive to manufacture, rugged in construction, easy to use and efficient in operation.

These and other objects will be readily evident upon a study of the following specification and the accompanying drawing wherein:

FIG. 1 is a vertical view of the present invention shown in elevation and in section;

FIG. 2 is a top plan view of the present invention; and

FIG. 3 is an enlarged side view of the adjustable trough member showing the shooter ball in place thereon.

According to this invention, a barrel pool game device 10 is shown to include a barrel 11 having a bottom wall 11'. A resilient lining 12 is adhered in a suitable manner to the inner periphery of barrel 11 and extends downwards to the playing surface 13 of an inner wall 13' and extends upwards to the rim 14 which defines opening 15 in the upper extremity of barrel 11.

An elongated bar 16 is transversely carried within barrel 11 near its upper extremity and is fixedly secured thereto.

Slideable upon bar 16 is a sleeve 17 which may be tightened by means of a wing nut fastener 18 for a purpose which hereinafter will be described.

A plurality of playing balls 19 are placed upon surface 13 of wall 13' in a set-up circle 20 which may be positioned in any desired area upon the surface 13.

5 A shooter ball 21 is used to impact with balls 19 on surface 13. Sleeve 17 is provided with a post member 22 which is fixedly secured thereto at one end and is adjustably carried within lugs 23 secured to the underside of a trough member 24 and the angle of trough member 24 is adjustable by means of a wing nut fastener 25 so that the player may discharge a shooter ball 21 from any angle and place within barrel 11 through accommodation use of the sleeve 17 and the bar 16 in conjunction with angular adjustment of trough member 24.

10 A member 26 is fixedly secured to the underside of trough member 24 and has secured to it at one end, a spring 27 of which the opposite end is secured to a pivotable lever member 28 which is manually operated and secured to hinge 29, the hinge also being secured to member 26.

15 It will be noted that spring 27 will be adjusted to such tension that is necessary to hold lever 28 against the end of trough member 24 against the weight of the shooter ball 21.

20 When the players have adjusted sleeve 17 upon the bar 16 to a desired position and have also adjusted the angle of the trough member 24 the lever 28 is urged rearwards of trough member 24 and is released which will drive the shooter ball 21 out of the trough member 24 and downward upon the playing surface 13 in order to impact with a plurality of balls 19 to thus separate them.

25 If the shooter ball 21 should happen to fall into any one of the plurality of spaced apart apertures 30, then that player forfeits all of the target balls 19 and his turn, however, if the target balls 19 are broken and the shooter ball 21 is not lost, the target balls 19 are directed into apertures 30 in rotation, as long as the 30 proper numbered ball is hit first, all of the balls 19 received in apertures 30 on that shot may be counted towards the player's score.

35 After the balls 19 are set up in the circle 20 and have been spread apart on impact, the players can use the 40 resilient lining sides 12 of barrel 11 to make shots from any angle desired, the balls 19 being apertured in rotation.

45 When the balls 19 fall into any one of the plurality of apertures 30, they will strike the chute 31 which is angled towards the front of device 10 and will remain there until the players decide to remove them from the chute through barrel 11.

50 It shall be noted that barrel 11 is weighted at its lower extremity in order to prevent tipping of barrel 11.

55 What I claim is:

1. A barrel pool game device comprising:
- a. a cylindrical barrel;
- b. A resilient lining on the inside of said barrel;
- c. A plurality of target balls;
- d. a shooter ball for impacting with a plurality of said target balls;
- e. a lower inner wall disposed within said barrel for arranging said target balls;
- f. means including a trough carried by said barrel for adjustably delivering said shooter ball to any desired position for impact with said target balls arranged on said lower wall;

- g. means for holding said trough a predetermined distance above said lower wall;
  - h. Wing nut fastener means providing for adjustment of the angle and position of said trough;
  - i. lever means carried by said trough having attached 5 spring return means cooperating with said lever means for manually displacing said shooter ball from said trough;
  - j. a plurality of target apertures spaced about the circumference of said barrel through which any of 10 said target or shooter balls may fall;
  - k. chute means provided below said lower wall for directing balls falling through said target apertures; and
  - l. a retrieval aperture for removal of balls from below 15 the lower wall provided at the lowest portion of said chute means.
2. The combination according to claim 1, wherein:
- a. said chute means being fixedly secured at an angle so as to gravity feed said target balls to said 20 retrieval aperture in the outer peripheral wall of said barrel;
  - b. said lower wall being fixedly secured to the inner

- periphery of said barrel;
  - c. said barrel having an upper rim;
  - d. said resilient lining being adherently attached to the inner periphery of said barrel and extending upward from the inner wall to the rim of the barrel; and
  - e. said rim defining an opening smaller than that of the outside diameter of the barrel.
3. The combination according to claim 2, wherein:
- a. said adjustable means includes a post member and a sleeve;
  - b. said holding means comprises a bar member fixedly secured to the inner periphery of said barrel and horizontal with the lower wall of said barrel;
  - c. said sleeve slidably carried on said bar member;
  - d. said post member fixedly secured to said sleeve and carrying said trough member; and
  - e. said sleeve adjustable on said bar by means of a wing nut fastener and enabling players of said game to position said trough to any traverse point desired within said barrel.
